BIRD CAGE

Adolph Adamson, Lomita, Calif.

Application October 7, 1955, Serial No. 38,275

Term of patent 14 years

(Cl. D31—2)

Fig. 1 is a front perspective view of a bird cage embodying my new design, in which the front access door is shown in open position; and

Fig. 2 is a rear perspective view of Fig. 1 showing the right-hand trough of Fig. 1 in released and partially removed position and showing the right-hand end of the dropping tray in partially extended relationship.

I claim:

The ornamental design for a bird cage, substantially as shown.
